UNITED STATES PATENT OFFICE.

THORVALD J. PETERSEN, OF NEW YORK, N. Y., ASSIGNOR TO THE GLOBE LIGHTING FIXTURE MANUFACTURING COMPANY, OF BROOKLYN, NEW YORK, A COPARTNERSHIP.

DESIGN FOR A WALL BRACKET FOR LIGHTING FIXTURES.

Application filed May 21, 1928. Serial No. 26,793. Term of patent 3½ years.

To all whom it may concern:

Be it known that I, THORVALD J. PETERSEN, a citizen of the United States, residing at New York city, in the county of New York and State of New York, have invented a new, original, and ornamental Design for a Wall Bracket for Lighting Fixtures, of which the following is a specification, reference being had to the accompanying drawing, forming part hereof, in which—

Fig. 1 is a top plan view; and
Fig. 2 is a front elevation, showing my new design.

I claim:

The ornamental design for a wall bracket for lighting fixtures, as shown.

THORVALD J. PETERSEN.
